UNITED STATES PATENT OFFICE

2,446,683

BRASSIÈRE

Pierre Amyot, Quebec, Quebec, Canada

Application August 22, 1944, Serial No. 550,581

1 Claim. (Cl. 2—42)

1

This invention relates to improvements in brassières.

The problem of providing a close-fitting brassière which gives the desired bust-molding and supporting effect without discomfort to the wearer has usually been dealt with by incorporating, in the central portion of the brassière, a tensioning strap or elastic fabric insert including rubber threads or yarns which extend in the circumferential direction of the brassière and impart stretch characteristics enabling the brassière to stretch easily to conform closely to the bust when the brassière is secured in place.

The existing scarcity of rubber, as well as certain disadvantages and inconveniences attending the use of rubber threads in brassières has led to the adoption of other expedients for providing resilient stretchability in the circumferential direction. Inserts of various types of knitted fabrics have been tried, as well as inserts of woven fabric cut and inserted on the bias but these and other expedients have not only failed to provide the requisite degree of resilient stretchability but have also made it difficult to provide a brassière that will cling closely to the bust with the desired bust-molding and supporting tension.

The present invention has been developed to meet the needs of the existing situation and consists in providing, in the front central portion of a brassière, a specially shaped insert made of woven fabric which has no rubber threads incorporated therein but has considerable elastic stretch in one direction, the shape, construction, and method of incorporating said insert being such that it imparts to the brassière stretch and form-fitting characteristics which have heretofore been obtainable only by the use of rubber-yarn inserts with their characteristic disadvantages.

Proceeding now to a more detailed description of the invention reference will be had to the accompanying drawings, in which—

Fig. 1 is a front view of a brassière embodying my invention.

Fig. 2 is a rear view of said brassière.

Fig. 3 is a front elevational view of the woven fabric insert which is incorporated in the front central portion of the brassière shown in Figs. 1 and 2.

Fig. 4 is a transverse sectional view taken substantially along the line 4—4 of Fig. 3.

Fig. 5 is a view similar to Fig. 3 but showing a slight modification.

Fig. 6 is a sectional view along the line 6—6 of Fig. 5.

In these drawings my improved brassière is 55 this fabric is cut, folded and inserted in the bras-

2

generally indicated at 4. It comprises a pair of breast-pocket sections 5 having their inner portions joined to a central section 6 and their outer portions joined to side sections 7, the latter being 5 equipped with complementary fastening devices 8 and 9, of the hook and eye type, for securing the brassière in place about the body of the wearer. Conventional shoulder straps 10 are shown connected between the breast-pocket sections 5 and the side sections 7.

The breast-pocket sections 5 and the side sections 7 are made of any suitable material and preferably have little or no stretch in any direction.

15 The central section 6 comprises upper and lower parts which are sewn together in overlapping relation. The upper part of this section is indicated at 12 and comprises a panel formed with concavely curved side edges which are sewn to the breast-pocket sections 5 and a V-shaped lower end portion 12a which overlaps and is sewn to the central portion of the lower part 13 of section 6.

25 The part 13 of section 6 comprises a piece of woven fabric which is cut and folded upon itself to provide an insert having a straight upper edge portion 14, concavely curved upper edge portions 15, straight end edge portions 16 and a full-length concavely curved lower edge portion 17. The 30 fabric is folded so that the body of the insert is of two-ply thickness while the lower edge portion is of four-ply thickness. In the construction shown in Figs. 1 to 4 inclusive the four-ply thickness at the lower edge of the insert is obtained by turning the lower edges of the two body-forming plies so that said turned edges are disposed to lie one upon the other at one side of the body portion of the insert. In the modified construction shown in Figs. 5 and 6, the four-ply thickness 35 is obtained by turning the lower edges of the fabric inwardly between the two body-forming plies.

40 The part 13 of section 6 is secured in place by sewing the curved upper edge portions 15 to the breast-pocket sections 5 and sewing the end edges 16 to similar end edges 19 of portions of the side sections 7 which underlie the breast-pocket sections 5.

45 The part 13 of section 6 is made of woven fabric which includes no rubber yarns but is woven so that the fabric is relatively non-stretchable in the direction of its length but is capable of considerable elastic stretch and contraction in the direction of its width. In making the part 13 50 this fabric is cut, folded and inserted in the bras-

sière so that its direction of stretch is in the circumferential direction of the brassière. The four-ply thickness at the lower edge of part 13 prevents edge-curling and controls the stretch characteristics of this part of the brassière.

The specific contour of part 13 is an important factor which enhances the close-fitting and breast-molding characteristics of the brassière in addition to providing a degree of circumferential elasticity equal to that previously obtainable only by the use of rubber yarn. In this connection it may be explained that when the brassière is secured about the body of the wearer the part 13 is tensioned and the concave lower edge 17 permits part 13 to stretch until said edge 17 becomes approximately a straight line. The stretching along the curved upper edges 15 of part 13 causes the insert to exert a desirable uplifting and molding effect on the adjacent portions of the breasts, thus giving the latter a desirable uplifted and well separated appearance.

Having thus described what I now conceive to be the preferred embodiment of this invention it will be understood that various modifications may be resorted to within the scope and spirit of the appended claim.

I claim:

A brassière comprising breast-pocket sections, side sections joined to the outer side and outer lower edge portions of said breast-pocket sections and a central section joining the inner side and inner lower edge portions of said breast-pocket sections, said central section comprising upper and lower parts sewn together in overlapping relation, the upper part of said central section comprising a single ply panel formed with concavely curved side edges joined to convexly curved up-

per inner side edges of the breast-pocket sections, said upper part of said central section being formed with a lower end overlapping the central portion of the lower part of said central section, said overlapping end being sewn along its lower marginal edge to the central portion of the lower part of said central section, said lower part of said central section comprising a woven fabric folded to provide a two-ply insert having the fold line at the upper edge thereof, said edge presenting a straight central portion and concavely curved portions lying at opposite sides of said central portion and sewn to the inner lower edge portions of said breast-pocket sections, said insert also presenting straight end edges sewn to corresponding end edges of portions of the side sections which extend beneath and underlie the breast-pocket sections and a full-length concavely curved lower edge portion, said insert consisting entirely of inelastic yarns woven so that, by virtue of its shape and weave, the insert is relatively non-stretchable in the vertical direction of the insert and is capable of considerable elastic stretch in the circumferential of the insert.
